DESIGN FOR A TWEEZER

John M. Shonta, Detroit, Mich.

Application January 6, 1944, Serial No. 112,184

Term of patent 14 years

(Cl. D86—10)

To all whom it may concern:

Be it known that I, John M. Shonta, a citizen of the United States, residing at Detroit, in the county of Wayne, and State of Michigan, have invented a new, original, and ornamental Design for Tweezers, of which the following is a specification, reference being had to the accompanying drawing, forming a part thereof.

I claim:

The ornamental design for a tweezer, as shown.

JOHN M. SHONTA.
